(57) **CLAIM**

The ornamental design for a set of knife and fork, as shown and described.

DESCRIPTION

FIG. 1 is an exploded top perspective view of a set of knife and fork, showing my new design;

FIG. 2 is a top perspective view thereof, shown in assembled condition;

FIG. 3 is a top perspective view of thereof, shown in partially assembled condition;

FIG. 4 is a bottom, front, left-side perspective view thereof, shown without the fork for ease of illustration;

FIG. 5 is a top, rear, right-side perspective view thereof shown without the fork for ease of illustration;

FIG. 6 is a front elevation view thereof shown without the fork for ease of illustration;

FIG. 7 is a rear elevation view thereof shown without the fork for ease of illustration;

FIG. 8 is a left-side view thereof shown without the fork for ease of illustration;

FIG. 9 is a right-side view thereof shown without the fork for ease of illustration;

FIG. 10 is a top plan view thereof shown without the fork for ease of illustration;

FIG. 11 is a bottom plan view thereof shown without the fork for ease of illustration;

FIG. 12 is a top, rear, left-side perspective view thereof, shown without the knife for ease of illustration;

FIG. 13 is a bottom, front, right-side perspective view thereof, shown without the knife for ease of illustration;

FIG. 14 is a front elevation view thereof shown without the knife for ease of illustration;

FIG. 15 is a rear elevation view thereof shown without the knife for ease of illustration;

FIG. 16 is a left-side view thereof shown without the knife for ease of illustration;

FIG. 17 is a right-side view thereof shown without the knife for ease of illustration;

(Continued)

FIG. 18 is a top plan view thereof shown without the knife for ease of illustration; and,

FIG. 19 is a bottom plan view thereof shown without the knife for ease of illustration.

The broken lines in the drawings depict portions of the set of knife and fork kit that form no part of the claimed design.
